ICE TRAY

Maximilian Siebigterro, Detroit, Mich., assignor
to Charles B. Kemp, Grosse Pointe, Mich.

Application October 25, 1946, Serial No. 705,726

11 Claims. (Cl. 62—108.5)

1

This invention relates to an improved ice tray such as is used in domestic and commercial refrigerators and deals more particularly to an improved grid construction for an ice tray.

It is an object of the present invention to provide an ice tray grid construction which greatly facilitates the removal of ice cubes therefrom. It has heretofore been proposed to provide a grid construction wherein the walls of the individual compartments are bodily movable with respect to each other by hinging them together as is shown in Reissue Patent Number 20,693. A grid of my construction also produces bodily movement of the partition walls with respect to each other but in a different and improved manner. Instead of having the walls pivot as to each other, I provide a unique construction which permits the walls to slide with respect to their adjacent walls and thereby forcibly eject the ice blocks from the individual compartments.

In the drawings:

Figure 1 is a perspective view of an ice tray and grid embodying the preferred form of my invention.

Figure 2 is a sectional view taken along line 2—2 of Figure 1 and illustrating the preferred form of slotting the longitudinal and grid partitions.

Figure 3 is a view corresponding to Figure 2 showing the relative position of the parts during the removal of the ice cubes.

Figure 4 is a sectional view of a modified form of the invention shown in Figure 1.

Figure 5 is a sectional view of another modified form of the invention illustrating the use of an undivided longitudinal partition.

Referring to Figure 1, there is shown a conventional ice tray 10 having removably retained therein a grid, generally indicated as 12, for freezing a plurality of ice cubes. The grid 12 is made up of a plurality of alternately inclined wall sections 14 and 16 extending transversely of the tray. The tray is further divided by a longitudinal partition 18 which is preferably made in two separable members 20 and 22 shaped as shown. Wall sections 14 are secured to and movable with upper divider 20 and sections 16 are secured to and movable with lower divider 22. Although the sections may be secured to their respective dividers by various means I prefer to accomplish this by slotting sections 14 from the bottom to a point above the center thereof as shown at 24 in Figure 2 and forming angularly inclined cooperating slots 26 from the top of member 20 to below the center thereof. In like

manner sections 16 are secured to the lower divider 22 by cooperating slots 28 and 30. In this case slot 28 extends from the top of wall section 16 to a point below the center and slot 30 extends to the lower edge of divider 22.

Handle 32 is pivoted at 34 on the top divider 20 and has an extending tongue 36 which is adapted to cooperate with the contour of an upwardly disposed toe 38 on member 22 to move the top divider vertically and in the direction of toe 38 when handle 32 is pivoted upwardly. By displacing the top divider in this manner, it will be observed that wall sections 14 will be bodily moved with respect sections 16 and member 22 as shown in Figure 3. All wall sections 16 are provided with substantially the same movement by means of a heel 40 and cam 42 arrangement at the other end of partition 18 which serves to maintain the top and bottom dividers in parallel relationship during movement, and thereby move walls 16 in inclined parallel planes.

It will be realized, of course that in some instances tongue 36 might not engage toe portion 38 in the manner described. It may merely slide over the toe; in which case member 22 will pivot about heel 40. With either mode of operation it will be observed that the ice blocks will be quickly and forcibly ejected from the tray when handle 32 is pulled upwardly. It will also be realized that the tray may be divided by a plurality of longitudinal partitions actuated by as many handles or interconnected to be operated by a single handle.

In Figure 4 I have shown a somewhat modified form of the structure shown in Figures 1 to 3 wherein the handle 32 is pivotally attached to both the upper and lower dividers, as at 34 and 44 respectively and is provided with an extension 66 which is adapted to engage the flanged edge 56 of the tray. Figure 4 also discloses another manner of securing sections 14 and 16 to their respective dividers. In this embodiment wall sections 14 and 16 are slotted at both the upper and lower edges as at 46 and 48 and dividers 20 and 22 are provided with inclined slots 50 and 52 at their adjacent edges. However, the movements of the wall sections by the action of handle 32 is the same as described for the structure of Figure 1 with the exception that the engagement of extension 66 with the edge of the tray moves the entire grid and serves to dislodge the ice blocks at the bottom of the tray.

A further modification of my grid construction is shown in Figure 5 wherein the longitudinal partition 54 comprises a single member and the

3

tongue extension 36 of handle 32 is adapted to engage a flange portion 56 at the upper edge of the tray. Alternately inclined slots 58 and 60 on partitions 54 engage cooperating slots 62 and 64 on wall sections 14 and 16 respectively. The combined length of slots 60 and 64 is greater than the height of section 16 so that while wall sections 14 will be raised with partition 54, sections 16 are adapted to remain depressed when handle 32 is pulled upwardly. The movement of sections 14 will therefore break the bond between the blocks and walls 14 and the relative movement of adjacent wall sections will serve to eject the blocks in a manner similar to that already described.

It will thus be seen that the various grids which have been described are of simple construction and can be manufactured very cheaply. The transverse wall sections may be loosely retained by their respective longitudinal members or they may be secured thereto to prevent them from falling off when the grid is cleaned or otherwise handled. While I have described but a few means by which the wall sections may be retained by the longitudinal members it is to be understood that they may be secured in any suitable manner, the important feature being the relative movement obtained between the adjacent walls when the longitudinal partition is moved in the manner described.

I claim:

1. An ice tray partition unit comprising a plurality of wall sections adapted to extend transversely of an ice tray and being alternately inclined relative to the bottom wall of the tray so that adjacent wall sections are disposed at an angle to each other, a longitudinal partition member which comprises upper and lower members movable with respect to each other, said wall sections being arranged so that all wall sections inclined in the same direction are movable with one of said longitudinal members and wall sections adjacent to said last mentioned sections are movable with the other longitudinal member, and means for moving said upper member in a combined upward and longitudinal direction relative to said lower member whereby the wall sections movable with said upper member are moved in parallel inclined planes.

2. An ice tray partition unit comprising a plurality of wall sections adapted to extend transversely of an ice tray and being alternately inclined so that adjacent wall sections are disposed at an angle to each other, a longitudinal partition member which comprises upper and lower members movable with respect to each other, said wall sections being arranged so that all wall sections inclined in one direction are movable with one of said longitudinal members and wall sections inclined in the other direction are movable with the other longitudinal member, and means for raising one end of said upper member whereby the wall sections attached thereto are bodily moved with respect to the wall sections attached to said lower member.

3. A sharp freezing container comprising longitudinal partition members, a plurality of alternately inclined transverse wall sections dividing the container into individual triangular compartments, one wall of each compartment being movable with one of said longitudinal members and another wall of said compartments being movable with a different longitudinal member, and means for moving one of said longitudinal members with respect to another to produce bodily movement of

4

one wall of each compartment with respect to another wall of said compartment.

4. A sharp freezing container comprising a longitudinal partition member which comprises upper and lower members relatively movable with respect to each other, transverse wall sections dividing the container into a plurality of compartments, the adjacent transverse walls of each compartment being alternately inclined, one of said adjacent walls of each compartment being secured to said upper member so as to be movable therewith, the other of said transverse walls being secured to said lower member and movable therewith, and handle means on one of said longitudinal members cooperating with the other longitudinal member for moving one of said members with respect to the other so as to produce movement of one of said adjacent walls of said compartments in the direction of inclination of its adjacent wall.

5. A sharp freezing container comprising a tray, a longitudinal partition in said tray which comprises adjacent upper and lower members movable with respect to each other, transverse partitions for dividing the substance to be frozen in the tray into a plurality of blocks, the adjacent wall sections being disposed at an angle to each other to form triangular compartments and arranged so that one wall is movable with said upper longitudinal member and the other wall is movable with said lower member, and handle means for separating said longitudinal members to produce movement of at least one wall of each compartment with respect to its adjacent wall, whereby a compressive force is exerted on the frozen block contained therein to facilitate its separation from the adjacent compartment walls.

6. A sharp freezing container comprising a tray, a longitudinal partition in said tray which comprises two longitudinal members positioned one above the other, transverse walls disposed in zigzag relation to divide the tray into a plurality of triangular compartments above and below said walls adapted to retain blocks of frozen substance, one of said walls of each compartment being movable with one of said longitudinal members and the adjacent transverse wall being movable with the other longitudinal member and handle means cooperating with said members to move one of said longitudinal members upwardly and longitudinally whereby at least one wall of said compartments is moved upwardly and longitudinally of said tray to partially eject the frozen blocks from within the compartments above said transverse walls.

7. A sharp freezing container comprising a tray, a longitudinal partition in said tray which comprises two longitudinal members positioned one above the other, transverse walls disposed in zigzag relation to divide the tray into a plurality of triangular compartments above and below said walls adapted to retain blocks of frozen substance, one of said walls of each compartment being movable with one of said longitudinal members and the adjacent transverse wall being movable with the other longitudinal member, and handle means interconnecting said longitudinal members for displacing said upper member in parallel spaced relation to said lower member, whereby those compartment walls movable with said upper member are displaced in parallel inclined planes and partially eject the frozen blocks from the compartments above said transverse walls.

75 8. A sharp freezing container comprising a

tray, a plurality of alternately inclined transverse partitions dividing the tray into a plurality of triangular compartments, and a longitudinal partition extending through and supporting said transverse partitions, said transverse partitions being so supported as to permit one transverse compartment partition to slide with respect to its adjacent transverse partition when said longitudinal partition is raised within said tray.

9. A sharp freezing container comprising a tray, a plurality of alternately inclined wall sections extending transversely of said tray, a longitudinal partition supporting said wall sections and means for moving said longitudinal partition to produce a sliding movement of the wall sections inclined in one direction with respect to the adjacent wall sections inclined in the other direction.

10. A sharp freezing container comprising a tray and a removable partition unit adapted to divide the tray into a plurality of triangular shaped compartments and comprising a longitudinal dividing member, a plurality of alternately inclined transverse wall sections secured to said dividing member, and means for producing bodily movement of one transverse wall of each compartment with respect to its adjacent transverse wall section in the direction of inclination of said adjacent wall section whereby a compressive force is exerted on the ice blocks in said

compartments to facilitate their separation from the remainder of the compartment walls.

11. A sharp freezing container comprising a tray, a plurality of alternately inclined wall sections extending transversely of said tray and dividing the tray into a plurality of triangular compartments, a longitudinal member extending through said wall sections, one of said wall sections of each compartment being movable with said longitudinal member and the other wall section being slidably engaged with said longitudinal member, and handle means for lifting said longitudinal member whereby said wall section movable therewith exerts a compressive force against a substance frozen in said compartment to facilitate its separation from the side walls of said tray and said other compartment wall.
